Primary Examiner—Selina Sikder

Assistant Examiner—Thomas Johannes

(74) Attorney, Agent, or Firm—Brinks Hofer Gilson & Lione

(57) **CLAIM**

The ornamental design for a power controller user interface, as shown and described.

DESCRIPTION

FIG. 1 is a perspective view of the power controller user interface showing our new design; and,

FIG. 2 is a front view thereof.

The broken lines are included for the purpose of illustrating environmental structure and form no part of the claimed design.

1 Claim, 2 Drawing SheetsFIG. 1

FIG. 2
